(57) **CLAIM**

The ornamental design for a bib with a pocket, as shown and described.

DESCRIPTION

FIG. 1 is a back perspective view of a bib with a pocket in a configuration where a body of the bib is withdrawn from the pocket.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a front perspective view of the bib with the pocket in a configuration where the body of the bib is folded into the pocket. The surface of the pocket shown in FIGS. 8-14 is the inside surface of the pocket illustrated in FIGS. 1-7.

FIG. 9 is a front elevation view thereof.

FIG. 10 is a back elevation view thereof.

FIG. 11 is a right side elevation view thereof.

FIG. 12 is a left side elevation view thereof.

FIG. 13 is a top plan view thereof; and,

FIG. 14 is a bottom plan view thereof.

The dashed broken lines depict portions of the bib with the pocket that form no part of the claimed design. The dot-dashed broken lines represent a boundary of the claim, and form no part of the claimed design. The claimed design extends to the dot-dashed broken line boundary.
